UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

INCLOSED SWITCH.

Application filed April 26, 1920. Serial No. 376,801.

My invention relates particularly to improvements in constructions of the character of the Sutherland Patent #1,288,740, and the Knudson Patent #1,310,163, which are commonly known as safety switches.

It is desirable to normally lock the switch in its open circuit position when the cover is open so as to prevent accidents. It is also desirable to lock the cover closed when the switch is in the on or closed circuit position. On the other hand, it is desirable to permit the cover to be opened by inspectors or other authorized individuals without opening the circuit.

It is my main object in a construction of this character to provide means for permitting the opening of the cover while the circuit is closed. I accomplish this by the use of a system of interlocking parts, one of which is adapted to be retracted by means of a key so as to release the cover without affecting the switch. I have so constructed the parts as to insure the return of the parts to their normal condition when the key is withdrawn so as to avoid leaving the locking mechanism inoperative.

Fig. 1 is a front view of a construction embodying the improvements of my invention, the operating handle being shown in the closed circuit or on position.

Fig. 2 is a front view showing the cover of the receptacle open and the switch also open.

Fig. 3 is a fragmentary side view and partial section showing the interlocking or safety catch mechanism with the cover partly opened and the handle in the position it would occupy when the circuit is open, the key as shown in the cover.

Fig. 4 is a similar view but with the handle in the on position and the cover closed and omitting the key.

Fig. 5 is a sectional view in the plane of the line 5—5 of Fig. 4 on a larger scale showing the safety mechanism.

The receptacle or box consists of a body 6 with a hinged cover 7. The switch mechanism is preferably carried by an insulating base 8 mounted within the receptacle. The switch mechanism may be of any suitable type. In this case, I have shown an ordinary double bladed knife switch with two blades 9—9, each of which has a hinge post or support 10 and a stationary contact 11. The

two blades are connected by an insulating cross piece 12 and adapted to be operated by an external handle 13 which is hinged or pivoted in the body of the box and connected to the cross piece 12 by an interior arm 14.

The latch member 15 is pivoted at 16 preferably in a housing 17 secured to one side of the box. A spring 18 presses the member 15 toward the hub of the handle 13, so that the catch 19 is adapted to interlock with the shoulder 19' carried by the handle when the switch mechanism is in the off or open circuit position as shown in Figs. 2 and 3. This prevents the operation of the switch when the parts are in this position.

The member 15 also has an inclined abutment 20 adapted to be engaged by the stop pin or bolt 21 carried by the cover when the cover is closed so as to tilt the member 15 into the unlocked position of Fig. 4 and permit the operation of the handle and switch. The member 15 also has a hook 22 adapted to engage the stop pin 21 when in the position of Fig. 4, and prevent the opening of the cover when the switch is in the on or closed circuit position of Fig. 4.

This stop pin 21 is slidably mounted in a support 23 secured to the inside of the cover. A spring 24 normally presses the stop pin outwardly so that it engages the inside of the flange 7' of the cover. The cover is provided with a slot 25 for a key 26 and the stop pin 21 is provided with a groove 27 adapted to receive the blade of the key 26 so that upon rotation of the key the stop pin 21 may be retracted. The parts are so constructed in proportion that the key cannot be withdrawn without first allowing the stop pin 21 to be projected by the spring 24.

When it is desired to open the cover for the purpose of inspection of the switch when the circuit is closed, it is simply necessary to insert the key in the opening 25 and retract the stop pin 21 from the hook 22. The cover may then be opened and the switch may be afterward thrown to the off position if desired. Upon the withdrawal of the key, the stop pin 21 will automatically be protruded into position to engage the inclined abutment 20 when the cover is closed so as to automatically retract the member 15 and permit the switch to be

closed. In case it is attempted to close the cover with the switch on and the key out, the stop pin 21 will engage the outer face of the hook 22 so that the cover cannot be closed without either retracting the stop pin 21 or throwing the switch to the off position. As an additional precaution the box may be provided with lugs such as 28 and 29 which are adapted to be secured together by a padlock or seal. Other modifications or additions will occur to those familiar with this art.

I claim:

1. In an inclosed switch, a switch casing, a movable cover therefor having a key hole, a flange on said cover, a latch member carried by said casing, a bolt carried by said cover and normally pressing against said flange, a switch element in said casing, a handle for operating said switch, and means for causing said latch member and bolt to be held in engagement to lock the cover closed when the switch is in closed circuit position, said bolt being movable by means of a key inserted through the hole in the cover to cause a disengagement of said bolt and latch member to permit the cover to be

opened when the switch is in closed circuit position.

2. In an electric switch construction, the combination of a box having a hinged cover with a flange overlapping an edge of the box, a switch mounted in a box, interlocking mechanism between the switch and the cover consisting of a latch member carried by the box adjacent one side thereof, and a spring-pressed bolt mounted within said cover, said cover flange normally constituting an abutment for said bolt.

3. In an electric switch construction, the combination of a box having a hinged cover with a flange overlapping an edge of the box, a switch mounted in a box, interlocking mechanism between the switch and the cover consisting of a latch member carried by the box adjacent one side thereof, and a bolt supported entirely within said cover and adapted to interlock with said latch, said cover flange serving as a stop for said bolt and said cover having a slot adjacent said bolt for admitting a key to operate said bolt.

BENJAMIN E. GETCHELL.
